US0D1061468S

(12) **United States Design Patent** (10) **Patent No.:** **US D1,061,468 S**
(45) **Date of Patent:** **** Feb. 11, 2025**

(54) **SMARTPHONE**

(71) Applicant: **Schiedermair Rechtsanwaelte**,
Frankfurt am Main (DE)

(72) Inventors: **Mark Shipard**, Sternberg (DE); **Dong Hee Suh**, Munich (DE)

(73) Assignee: **Schiedermair Rechtsanwaelte**,
Frankfurt am Main (DE)

(**) Term: **15 Years**

(21) Appl. No.: **29/800,785**

(22) Filed: **Jul. 23, 2021**

(30) **Foreign Application Priority Data**

Jan. 26, 2021 (WO) WIPO101304

(57) **CLAIM**

The ornamental design for a smartphone as shown and described.

DESCRIPTION

FIG. 1 is a front perspective view of a smartphone according to the present invention.

FIG. 2 is a back perspective view of the smartphone of FIG. 1.

FIG. 3 is a front view of the smartphone of FIG. 1.

FIG. 4 is a back view of the smartphone of FIG. 1.

FIG. 5 is a left side view of the smartphone of FIG. 1.

FIG. 6 is a right side view of the smartphone of FIG. 1.

FIG. 7 is a top view of the smartphone of FIG. 1; and,

FIG. 8 is a bottom view of the smartphone of FIG. 1.

The broken lines are directed to environment; the broken lines form no part of the claimed design.

1 Claim, 8 Drawing Sheets
